(57) **CLAIM**

The ornamental design for a modular rack as shown and described.

DESCRIPTION

FIG. 1 is a front, top, and right perspective view of a modular rack, showing my new design in a first configuration of use;

FIG. 2 is a front, top, and left perspective view thereof;

FIG. 3 is a front elevational view thereof;

FIG. 4 is a back elevational view thereof;

FIG. 5 is a left side view thereof;

FIG. 6 is a right side view thereof;

FIG. 7 is a top view thereof;

FIG. 8 is a bottom view thereof;

FIG. 9 is a front, top, and right perspective view in a second configuration of use;

FIG. 10 is a front, top, and left perspective view in a second configuration of use;

FIG. 11 is a front, top, and right perspective view in a third configuration of use;

FIG. 12 is a front, top, and left perspective view in a third configuration of use;

FIG. 13 is a front, top, and left perspective view in a fourth configuration of use; and,

FIG. 14 is front, top, and right perspective view in a fourth configuration of use.

The drawings are shown with a symbolic break in the length of the sides of the article. The appearance of any portion of the article between the break lines form no part of the claimed design.

The even-length broken lines showing the remainder of the modular rack are for environmental purposes only and form no part of the claimed design.

The broken lines consisting of dot-dash lines are boundary lines that show that the claimed design extends to the boundary line, but does not include the boundary line.

1 Claim, 14 Drawing Sheets
